(57) CLAIM

The ornamental design for a wall outlet safe, as shown and described.

DESCRIPTION

FIG. 1 is a first perspective view of a wall outlet safe showing my new design;

FIG. 2 is a front elevation view thereof;

FIG. 3 is a back elevation view thereof;

FIG. 4 is a first side elevation view thereof;

FIG. 5 is a second side elevation view thereof;

FIG. 6 is a top plan view thereof;

FIG. 7 is a bottom plan view thereof; and,

FIG. 8 is a second perspective view thereof, shown in a used condition with an electrical face plate shown in broken lines. The broken lines in FIGS. 2 and 8 represent unclaimed portions of the wall outlet safe and form no part of the claimed design.

1 Claim, 8 Drawing Sheets
